J. BOLTON.

Hot-Air Furnace.

No. 10,333.

Patented Dec. 20, 1853.

UNITED STATES PATENT OFFICE.

JAMES BOLTON, OF RICHMOND, VIRGINIA.

HOT-AIR FURNACE.

Specification of Letters Patent No. 10,333, dated December 20, 1853.

To all whom it may concern:

Be it known that I, JAMES BOLTON, doctor of medicine, of the city of Richmond, in the county of Henrico and State of Virginia, 5 have invented a new and Improved Mode of Constructing Warm-Air Chambers; and I do hereby declare that the following is a full and exact description thereof, reference being had to the accompanying drawings 10 and to the letters of reference marked thereon.

The nature of my invention consists in dividing an air chamber (surrounding a stove, furnace, pipe or other contrivance for 15 heating air) by partitions into separate compartments, each of which is to be connected with one or more separate warm air flues, so that each flue or set of flues may be supplied with warm air from that compartment 20 exclusively with which the flue or set of flues may be connected.

To enable others skilled in the art to make and use my invention, I will proceed to describe its construction and operation.

25 I construct my warm air chamber according to the plan described in my specification of an improvement in warm air chambers for which Letters Patent of the United States were issued to my assignee, Charles 30 D. Yale, dated the twenty-sixth day of April, one thousand eight hundred and fifty three, because I consider this the best form of air chamber and almost the only form adapted to the improvement herein de- 35 scribed; but in order to obviate the incon- 40 venience usually arising from some of the apartments which are designed to be warmed receiving less than their due proportion of warm air (which is well known to be a 45 usual occurrence owing to some apartments being more favorably situated in regard to elevation and proximity to the air chamber and consequently drawing off more than their due supply of warm air, an incon- 50 venience which is especially liable to occur when there is a moderate fire in the furnace and consequently a moderate supply of 55 warm air by the chamber) I attach one or

more sheets of iron to the wall or inclosure of the air chamber by their outer edges, 50 placed in a vertical direction, their faces being placed in radii passing from the vertical axis of the furnace, and I attach their inner edges closely to the opposite external surface of the furnace. I thus place vertical airtight partitions in my air chamber, as shown at letters A A A A. These partitions I fasten accurately together in the center of the chamber where the furnace or pipe is wanting. The upper and lower edges of 60 these partitions I attach to the upper and lower surfaces of the inclosure of the air chamber. The effect of this arrangement is to divide the air chamber into separate compartments made as nearly as may be airtight 65 and consequently the air from the moment it enters the chamber is conveyed by one continuous conduit to the apartment for which it is designed. At the upper part of each of these partitions I place a valve B, for the 70 purpose of throwing the air of two or more compartments into one, if it should be desired. I enter the upper part of each of these compartments by one or more warm air flues, which are supplied with warm air 75 by the compartment to which they are attached. When the warm air rises in the compartments as described it cannot pass from one to another unless the valve between them be opened; nor can it pass from a sin- 80 gle compartment to any other flues than those with which it is connected.

What I claim as my invention and desire to secure by Letters Patent is—

The division into compartments of the air 85 chamber surrounding a stove, furnace, pipe or other contrivance for warming the air which it contains so that the warm air may be drawn off by flues from each compartment without interfering with the supply 90 of warm air from the other compartments.

JAMES BOLTON. [l. s.]
